(57) **CLAIM**

The ornamental design for a hacksaw frame, as shown and described.

DESCRIPTION

FIG. 1 shows a left side view of a first embodiment of a hacksaw frame according to the present invention.

FIG. 2 shows a right side view of the hacksaw frame embodiment of FIG. 1.

FIG. 3 shows a top view of the hacksaw frame embodiment of FIG. 1.

FIG. 4 shows a bottom view of the hacksaw frame embodiment of FIG. 1.

FIG. 5 shows a front view of the hacksaw frame embodiment of FIG. 1.

FIG. 6 shows a rear view of the hacksaw frame embodiment of FIG. 1.

FIG. 7 shows a left side view of a second embodiment of a hacksaw frame according to the present invention with potential saw blade positions shown in phantom lines.

FIG. 8 shows a right side view of the hacksaw frame embodiment of FIG. 7.

FIG. 9 shows a top view of the hacksaw frame embodiment of FIG. 7.

FIG. 10 shows a bottom view of the hacksaw frame embodiment of FIG. 7.

FIG. 11 shows a front view of the hacksaw frame embodiment of FIG. 7.

FIG. 12 shows a rear view of the hacksaw frame embodiment of FIG. 7.

FIG. 13 shows a left side view of a third embodiment of a hacksaw frame according to the present invention with potential saw blade positions shown in phantom lines.

FIG. 14 shows a right side view of the hacksaw frame embodiment of FIG. 13.

FIG. 15 shows a top view of the hacksaw frame embodiment of FIG. 13.

FIG. 16 shows a bottom view of the hacksaw frame embodiment of FIG. 13.

FIG. 17 shows a front view of the hacksaw frame embodiment of FIG. 13; and,

FIG. 18 shows a rear view of the hacksaw frame embodiment of FIG. 13.

Throughout the Figures, aspects shown in broken lines are not considered a portion of the claimed ornamental design.
